(57) **CLAIM**

The ornamental design for a lid/tray package for an inhalation device, as shown and described.

DESCRIPTION

FIG. 1 is a top perspective view of a lid/tray package for an inhalation device, showing our new design without the lid in a typical usage condition;

FIG. 2 is a top plan view thereof;

FIG. 3 is a bottom plan view thereof;

FIG. 4 is a side view thereof;

FIG. 5 is an opposite side view thereof;

FIG. 6 is an end view thereof;

FIG. 7 is an opposite end view thereof;

FIG. 8 is a top perspective view thereof, showing our design with the lid sealed to the tray portion in a typical usage condition;

FIG. 9 is a top plan view thereof;

FIG. 10 is a bottom plan view thereof;

FIG. 11 is a side view thereof;

FIG. 12 is an opposite side view thereof;

FIG. 13 is an end view thereof;

FIG. 14 is an opposite end view thereof;

FIG. 15 is a perspective view thereof, showing the lid portion of our design in isolation for clarity of illustration; and,

FIG. 16 is a plan view thereof.
